CLOSURE AND METHOD AND APPARATUS
FOR APPLYING SAMEGeorge W. Booth, Baltimore, Md., assignor to
Crown Cork & Seal Company, Inc., Baltimore,
Md., a corporation of New YorkApplication November 4, 1932, Serial No. 641,288
Renewed February 3, 1934

6 Claims. (Cl. 226—83)

The present invention relates to specific developments under the convention described and claimed in my copending United States application Serial No. 553,464, filed July 27, 1931.

Serial No. 553,464 discloses the idea of sealing a container by means of a substantially flat ductile disc which is smoothly ironed and drawn over the upper external surface of a bead surrounding the container mouth, the marginal portion of the disc taking a natural locking crimp under the bead. The said application, while not limited as to the extent of the ironed zone of the closure, shows an expandible throat of such normal diameter as to exert an ironing action on the closure disc substantially from the top of the bead to its line of maximum circumference. In other words, the major direct conforming action of the throat is an ironing action, only a small disc area being conformed to the bead by a sole drawing action. The present invention relates to a specific development wherein this relation is reversed, the conformation of the closure being obtained through a relatively small ironing engagement by the throat, free buckling of the closure margin occurring as contemplated in the original invention. The present invention relates to a new method, to the means for carrying out the new method, such means including either an expandible or non-expandible throat, and to the sealed container.

The invention will be described with reference to the accompanying drawings, in which:

Figure 1 is an axial section through a capping head, a container neck and a closure disc in initial position.

Figure 2 shows the elements of Figure 1, in a second relation.

Figure 3 shows the elements of Figure 1, in a third relation.

Figure 4 shows the elements of Figure 1, in a fourth relation.

Figure 5 shows the elements of Figure 1, modified as to the throat, in initial position.

Figure 6 shows the elements of Figure 5, in a second position.

Figure 7 shows the elements of Figure 5, in a third position.

Figure 8 shows the elements of Figure 5, in a fourth position.

Figure 9 is an elevation partly in section of the throat of Figures 1 to 4.

Figure 10 is a plan view of the throat of Figure 9.

Figure 11 is an elevation partly in section of the throat of Figures 5 to 8.

Figure 12 is a plan view of the throat of Figure 11.

Figure 13 is a diametric section of one form of closure disc.

Figure 14 is a plan of the disc of Figure 13. 60

Figure 15 is a diametric section of another suitable form of disc, and

Figure 16 shows an elevation, the top of a bottle with the closure cap applied in accordance with the present invention. 65

Referring first to Figures 13 and 14, reference numeral 20 designates a circular substantially flat closure disc of ductile material, ordinarily metal. As here shown, the disc is single-ply and its central portion is slightly upwardly offset to 70 leave an annular marginal portion.

According to Figure 15, the disc comprises a ply 21 of ductile material and an overall liner 22 of relatively compressible material. This liner may be of any suitable material known in the art 75 and may be in the nature of an adhesively applied ply or in the nature of a coating. The disc is shown as being centrally offset as the disc 20 of Figures 13 and 14.

The described discs are merely shown as representative of the closure discs contemplated under the present invention, since the invention is not limited as regards the specific disc structure. 80

In Figures 1 to 4, reference numeral 23 designates generally a capping head carried by a neck 95 24, which, in turn, is supported in a support 25 for movement relative to the latter. An annulus 26 is positioned in the head beneath the top wall thereof and is secured to an external annulus 27 by means of studs 28 slidable in apertures in the top wall of the head. Interposed between a fixed flange or seat 29 and a superposed slidable ring 30, is a compression spring 31. A throat 32 has a top annular rib 33 supported on a ledge formed on ring 30, spring 31 holding the top edge of the 90 throat against annulus 26.

A presser tool 34 is arranged coaxially with throat 32 and is supported on annulus 26 by means of a cap 35, the latter being engaged by the rounded extremity of a stud 36, which is urged 100 downwardly by a compression spring 37, downward movement of the stud being limited by the abutment of its head 38 with a rib 39 formed in the neck.

The head also presents an annular ledge 40 105 beneath the lower end of throat 38. All of this construction is generally that shown in the copending application of Huntley and Rau, Serial No. 622,154, filed July 12, 1932, and consequently need not be described at great length here. 110

In Figure 1, a disc 20 is assumed to have been fed onto ledge 40 to be supported thereby and a bottle 41 is positioned in coaxial relation to the head beneath the disc. The mouth of bottle 41 has the usual bead 42, which has a top exterior surface outwardly convexed, that is of increasing diameter from its top to the line or plane of maximum circumference of the bead, the bead presenting a shoulder below this line.

Upon relative movement of the support and container to approach them coaxially, and assuming that the support is being moved downwardly, the cap 20 comes to rest on top of the bead and is centered thereon by reason of its central offset portion. The pressure tool 34, resting on the cap, holds the head against further downward movement with the support so that the support now moves downwardly relative to neck 24, eventually striking ring 27 and lowering annulus 26 and therewith throat 32 until the lower edge of the latter is closely approached to the top of the disc margin. This downward movement of the throat is limited by abutment of ring 27 with the top wall of the head. Further movement of the support 25 causes the presser tool to rise against spring 37, the throat beginning to bend the marginal portion of the cap as shown in Figure 2.

Throat 32 is solid and non-expansile as shown in Figures 1 to 4. Externally, it is substantially cylindrical, with the exception of rib 33, but internally its surface is that of a frustum of a steep inverted cone. The lower inner edge 32' of the throat has a diameter which is slightly less than the diameter of the bead 42 at its line of maximum circumference plus twice the thickness of the disc. Therefore, upon continued movement of the head, the edge 32' begins to iron the skirt of the cap immediately above the line of maximum circumference of the bead with a powerful action. This ironing action results in a perfectly smooth conformation of the skirt to the bead surface in the ironing zone and above this zone the skirt is powerfully drawn into smooth conformation with the upper bead surface.

In Figure 3, the edge 32' has substantially reached the line of maximum circumference of the bead and is effecting the ironing action just mentioned. The extreme marginal portion of the skirt is still guided on ledge 40, but is just about to leave the latter and does upon slight further movement of the head. Hereupon, the margin of the skirt below the line of maximum circumference of the bead takes a natural locking crimp under the shoulder, as shown in Figure 4. As shown in this latter figure, the throat has travelled downwardly to such an extent that its lower portion would tend to tuck the buckled skirt margin under the shoulder, but this tendency is purely incidental. The throat need not travel to any appreciable extent beyond the line of maximum circumference of the bead.

It will be understood that due to the relation of the diameter of edge 32' to the diameter of the bottle, a very powerful compressive force is exerted on the skirt as edge 32' comes to the line of maximum circumference of the bead and the skirt material is necessarily slightly compressed or thinned. It will be apparent, therefore, that the bottle bead can have no appreciable irregularity in the carrying out of the method. Since bottle beads frequently are not exactly true it is desirable, when using the described non-expansile throat, to use a closure having a liner such as 75 is shown in Figure 15. The liner 22 is relatively

compressible as compared to the ductile disc 21. In the use of this closure, therefore, the throat due to the compressibility of the liner does not strain the bottle top so severely as when the liner is omitted and the material of the liner readily accommodates itself to slight irregularities in the bead finish. The diameter of the edge 32' would, of course, be somewhat larger if a lined closure were to be used, and in general it may be said that the exact diameter of the edge 32' is determined by the thickness of the closure and its compressibility.

The neck of the bottle 41 is shown in Figure 16 with the cap 20 applied thereto. The smooth conformation of the skirt to the bead is clearly shown in this view, this conformation giving the closure a large contact area with the bead, so that a very efficient seal is afforded.

The structure shown in Figures 5 to 8 is exactly the same as that of Figures 1 to 4, with the exception of the throat. The throat 43, Figures 5 to 8, is made up of a number of segments 44, these being surrounded and held together for relatively expansive movement by a spring 45. Interiorly, throat 43 has normally exactly the same shape as the above described throat 32 and normally the edge 43' has the same diameter as the edge 32'. On the other hand, the diameter of the edge 43' may be somewhat less than the diameter of edge 32' in view of the expansibility of the throat 43.

The capping operation is carried out in exactly the same manner as described in connection with Figures 1 and 2 and the same four positions are illustrated in Figures 5 to 8. With the expansible throat there is, of course, less danger of breakage due to irregularities in the bead finish and, therefore, for general use the expansive throat is preferable to the non-expansive throat. For another thing the segments, after edge 43' has passed the line of maximum circumference of the bead, tend to pivot about this line and it will be noted that in Figures 7 and 8, the throat is reversely conical, as compared to Figures 5 and 6, which illustrate the normal condition of the throat. Due to this spreading of the lower end of the throat, it will be obvious that withdrawal of the head from the container is facilitated.

I wish to emphasize again the fact that while the invention contemplates the use of a substantially disc-like closure, it is not limited to the make-up of the closure which may be single-ply, plural-ply or multi-ply. It is merely essential that the closure have the necessary characteristic of ductility. Further, the invention is not limited as regards details of apparatus and I do not limit myself as to any of these particulars, except as in the following claims.

I claim:

1. The method of applying a ductile disc closure to a bead surrounding a closure mouth, the bead having an external convex surface above its line of maximum circumference and a shoulder below said line, said method comprising bending the positioned disc over said convex surface to form a skirt and ironing the skirt on the bead circumferentially substantially continuously from a circumferential line of the bead immediately adjacent said line of maximum circumference toward said last-named line, whereby the skirt portion in the ironing zone is smoothly conformed to the bead by the ironing action and the skirt portion between the ironing zone and the top of the bead is drawn into smooth conformation with the bead, the marginal portion of

- the skirt taking a natural locking crimp under said shoulder.
2. The method of applying a ductile disc closure to a bead surrounding a closure mouth, the bead having an external convex surface above its line of maximum circumference and a shoulder below said line, said method comprising bending the positioned disc over said convex surface to form a skirt and ironing the skirt on the bead circumferentially substantially continuously from a circumferential line of the bead immediately adjacent said line of maximum circumference toward said last-named line and in a circular path of fixed radius, whereby the skirt portion in the ironing zone is smoothly conformed to the bead by the ironing action and the skirt portion between the ironing zone and the top of the bead is drawn into smooth conformation with the bead, the marginal portion of the skirt taking a natural locking crimp under said shoulder.
3. Means for applying a ductile disc closure to a bead surrounding the mouth of a container, the bead having an external convex surface above its line of maximum circumference and a shoulder below said line, said means comprising a throat having a substantially circular lower inner edge, said circular edge having a normal diameter slightly less than the length of the diameter of the bead at its line of maximum circumference plus twice the thickness of the closure, means for relatively moving and coaxially approaching the throat and container to cause the positioned disc to bend it over said surface to form a skirt, the relative movement of the throat and container being continued to cause said circular edge to come at least to said line of maximum circumference, said edge ironing the skirt immediately adjacent said line to conform it smoothly to the bead and to draw the skirt portion above the ironed zone into smooth conformation with the bead, the ironing action causing the marginal portion of the skirt to take a natural locking crimp under said shoulder.
4. Means for applying a ductile disc closure to a bead surrounding the mouth of a container, the bead having an external convex surface above its line of maximum circumference and a shoulder below said line, said means comprising an expandible throat having a substantially circular lower inner edge, said circular edge having a normal diameter slightly less than the length of the diameter of the bead at its line of maximum circumference plus twice the thick-
- ness of the closure, means for relatively moving and coaxially approaching the throat and container to cause said edge to engage the positioned disc to bend it over said surface to form a skirt, the relative movement of the throat and container being continued to cause said circular edge to come at least to said line of maximum circumference, said edge ironing the skirt immediately adjacent said line to conform it smoothly to the bead and to draw the skirt portion above the ironed zone into smooth conformation with the bead, the ironing action causing the marginal portion of the skirt to take a natural locking crimp under said shoulder.
5. Means for applying a ductile disc closure to a bead surrounding the mouth of a container, the bead having an external convex surface above its line of maximum circumference and a shoulder below said line, said means comprising a throat having a substantially circular lower inner edge of constant diameter, said circular edge having a diameter slightly less than the length of the diameter of the bead at its line of maximum circumference plus twice the thickness of the closure, means for relatively moving and coaxially approaching the throat and container to cause said edge to engage the positioned disc to bend it over said surface to form a skirt, the relative movement of the throat and container being continued to cause said circular edge to come at least to said line of maximum circumference, said edge ironing the skirt immediately adjacent said line to conform it smoothly to the bead and to draw the skirt portion above the ironed zone into smooth conformation with the bead, the ironing action causing the marginal portion of the skirt to take a natural locking crimp under said shoulder.
6. In combination with an open-mouthed container having around its mouth an external bead which increases in diameter outwardly and downwardly from its top, a cap positioned over and closing the container mouth and comprising a shell of ductile material, said shell having a skirt smoothly ironed over the bead surface from a plane immediately adjacent the plane of maximum circumference of the bead toward the latter plane, whereby the skirt is conformed smoothly to the bead above the line of maximum circumference of the bead, the skirt having a marginal portion self-buckled into engagement with the bead to lock the cap on the container.
